FORMING DIES FOR CUTTING FABRIC COVERED WIRE RODS AND FORMING BUCKLES AND THE LIKE

Herman Gilgoff, Brooklyn, N. Y.

Application March 29, 1955, Serial No. 497,527

5 Claims. (Cl. 29—3)

This invention is directed to fabric or leather covered buckles, buckle bodies and like articles made of covered wire especially wherein the said articles are made of metal or other material either bent, formed or pressed to desired outline.

This invention relates particularly to forming dies and mechanism for cutting fabric covered wire rod to length and forming buckles and the like.

An object of this invention is to provide forming dies incorporating a pair of concurrently actuating bodily shiftable die members in which a bar is continuously under control from the start to the finish of all the bending, ejecting and collecting steps.

Another object of this invention is to provide a second step inbending device including parts forming an anvil effect during the first step and the second step to finish the bending of the buckle.

Another object of this invention is to provide motivating means for the cutting off lengths of wire to size and for the said first and second forming steps.

Another object of this invention is the provision of means employing a covered rod in manufacture of buckle frames or as a part of the decoration of an accessory. Also to act as a fastener for a belt.

Another object of this invention is to provide a mounting for buckle forming dies for buckles made of a cut length of covered wire without damaging the covering material, comprising an organization of parts including a carrier plate having an elongated slot centrally thereof, two elongated forming dies vertically slidably mounted on the plate, an upright bar mounted in alignment with the slot, the upright bar having a laterally extending member passing through the slot and carrying a horizontally positioned supporting bar for the vertically mounted forming dies, the forming dies respectively carrying two rollers in juxtaposed relation, a mandrel fixed to the front face of the carrier plate, two further forming dies pivotally mounted on the carrier plate below the mandrel and being spring-urged away from the mandrel, the vertical forming dies having bevelled sides contacting the ends of the wire and forming downwardly bent sides, the rollers being positioned to engage the bent sides and prevent rebending of the bent sides, the bevelled sides being in contacting relation with rollers positioned at the upper ends of the further dies when lowered and causing inbending of the bent wire ends into buckle forming relation and with the wire end portions in contact with the lower face of the mandrel, a stripper having two arms and being slidably mounted rearward of the carrier plate, the stripper being spring-urged in a direction rearward of the mounting, the carrier plate having two openings at the vertical sides of the mandrel and through which the stripper arms are movable forwardly to eject the completed buckle, means for moving the stripper forwardly to eject the buckle, and a collector member secured to the mandrel and shaped to direct the buckle rearwardly to a container positioned rearward of the front face of the mounting.

For the purpose of preventing damage to the covering

2

material, I have mounted two grooved and aligned rollers on each of the vertical forming dies, the faces of the rollers being grooved to engage the covering material on the wire of which the buckles are made. The rollers hold the bent wires of the buckle and prevent rebending of the bent wires and prevent damage to the covering material.

I have also mounted rollers at the upper ends of the further forming dies which serve to inbend the bent ends of the wire and these rollers prevent damage to the inbent covering material when the covered wire is bent into closing or buckle formation.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a fragmentary side elevation of a pedal operated press having my forming dies applied thereto.

Figure 2 is a front elevation of the forming dies shown in Figure 1.

Figure 3 is a view of a cut to length wire having two downwardly bent sides formed by vertically movable forming dies.

Figure 4 is a top plan view of a wire cutting-off mechanism.

Figure 5 is a cross-sectional view taken on line 5—5 in Figure 4.

Figure 6 is an end view of the mechanism shown in Figures 4 and 5.

Figure 7 is a cross-sectional view taken on line 7—7 in Figure 2 and showing a knife actuating arm and a stripper actuating cam in non-operating position.

Figure 8 is a cross-sectional view, taken on line 8—8 in Figure 2 and showing the vertical forming dies in lowered position.

In the illustrated embodiment of the invention, the numeral 10 indicates a foot pedal operated press of well known form embodying therein a bed 11 and a head 12.

Slidably mounted in the head 12 is a plunger rod 13 which has a reciprocatory movement imparted thereto by means of a foot pedal operated lever 14 which is pivotally mounted on a rod 15 secured in an extension of the head 12. The lever 14 has a bar 16 pivoted thereto on a pin 17 at the free upper end of the lever. The lower end of the bar 16 is pivotally mounted on a pin 18 at the upper portion of the rod 13.

Secured to the bed 11 by bolts 20 are two right angular brackets 21. The brackets have two upright legs 22 positioned in vertical alinement. Secured to the legs 22 by bolts 23 is an upwardly extending rectangular plate 24 facing the front of the press 10.

As best shown in Figures 2, the plate 24 has two arms or forming dies 26 positioned in equally spaced apart relation from a slot 27 at the center of the plate 24 and slidably mounted on the plate.

As shown in Figure 1, a T-bar 30 is secured to the lower face of the plunger rod 13 by a bolt 31. Secured to the upright portion 33 of the T-bar 30 by bolts 34 is an upright bar 35. The bar 35 has a lateral extension 36 secured thereto by a bolt 37. The extension 36 passes through the slot 27 and carries a horizontally positioned supporting bar 40 which is secured thereto by a bolt 41 passing through the bar 40 and threaded in the lateral extension 36. The bar 40 supports the forming dies 26.

The forming dies 26 respectively carry two-grooved rollers 43, 43. The rollers 43, 43 are positioned to engage a cut to length and bent wire 44 lying on the

upper face of a mandrel 45. The mandrel is secured to the front face of the carrier plate 24 by a bolt 46.

Two further forming dies 48, 48' are pivotally mounted to swing on the carrier plate 24 on bolts 49 threaded in the plate. The further dies 48, 48' and the bolts 49 are positioned considerably below the mandrel 45. Coil springs 50 have one end secured to the upper end portions 51 of the further forming dies 48, 48' and have their opposite ends 52 attached to stop plates 53 for limiting the sideways movements of the dies 48, 48'. The plates 53 are secured to the carrier plate 24 by bolts 54 passing through a tie plate 56. It is to be noted that rollers 55 are suitably rotatably mounted on the end portions 51 of the forming dies 48, 48'.

The vertical forming dies 26 have beveled lower sides 57 facing each other. When the forming dies 26 are moved downwardly, the beveled sides 57 contact both ends of the wire 44 and form downwardly bent sides 58 on the wire 44. The rollers 43 on the forming dies 26 are positioned in spaced apart relation so as to engage the bent sides 58 of the wire and prevent rebending or opening up of the bent sides.

On further downward movement of the upright forming dies 26, the beveled sides 57, contact the rollers 55 and swing the further forming dies 48, 48' inwardly and cause movement of the said dies against the lower ends of the bent wire and inbend the bent ends into buckle forming relation and with the wire end portions in contact with the lower face of the mandrel 45.

The carrier plate 24 has an opening 60 at each upright side of the mandrel 45. A stripper 61 has two arms 62 which are movable through the openings 60. The stripper 61 is carried by a bar 63 slidably mounted horizontally on two elongated bolts 64 which are suitably threaded in the carrier plate 24. The bar 63 and the stripper arms 62 are urged by coil springs 65 mounted on the bolts 64 to move rearwardly away from the carrier plate 24.

A cam 67 having an arcuate upper end portion is secured to the lower end of the upright bar 35 by a bolt 68. In the raised position of the mechanism, shown in Figures 1 and 2, the cam 67 has contacted the lower surface of the stripper bar 63 and has moved the said bar forwardly and has brought the stripper arms 62 through the slots 60 a distance sufficient to engage the completed buckle and to eject the buckle from the mandrel.

A collector member 70 in the form of a wire, is secured by the bolt 46 to the central portion of the mandrel 45.

The collector wire 70 is shaped to direct the finished buckle 71 rearwardly of the carrier plate 24 to a container 72 positioned rearward of the front face of the mounting and resting on a sub bed 11'.

Figure 4 is a top plan view of a cutting off mechanism 75 by means of which pieces of wire 44 are cut from a long length or from a coil of supply wire. The mechanism 75 comprises a housing 76 having a rectangular cavity 77 in which a knife 78 is resiliently supported.

As shown in Figure 5, the knife 78 is of right-angular form and comprises a horizontal portion 79 which is supported in raised position by coil springs 80 against an overhanging bracket 81. The knife 78 also comprises a vertical portion 83 which terminates at its lower end in an angularly directed cutting edge 84; the lower end of which is in line with the upper surface of a horizontal feed channel 85 through which the wire is fed into abutting relation with a stop member 86, shown in Figure 2. A slot 87 permits adjustment of the member 86.

Figure 6 is an end view of the cutting off mechanism shown in Figures 4 and 5 and showing a release bevel 96 on the housing 76.

Figures 2 and 7 show a knife actuating arm 90 pivotally mounted on a pin 91 in a bracket 92 which is fastened to the lower face of an overhanging portion of a carrier bar 93. The bar 93 is secured by bolts 94 to the upper

face of the horizontal bar 40 which carries the vertical forming dies 26.

The arm 90 has a substantially horizontal lower portion 96 for engaging and pressing the knife 78 down into cutting relation with the wire 44, against the action of the springs 80. Further downward movement of the arm 90 causes a bevelled lower surface 97 on the arm 90 to cause the arm to strike the bevelled surface 96 on the housing 76 and to slip off the knife and to swing away from the knife, which is then brought to normally raised position by the springs 80. A spring 95 urges the arm against the housing 76.

As shown in Figure 2, an upper positioning block 99 is fastened by a bolt 100 to the carrier plate 24 and is positioned with its lower surface in alignment with the upper surface of the wire 44. There has also been provided a retaining bar 101 which is secured by the bolt 46 and extends below the mandrel 45 and provides a retaining surface for the lower bent portions of the buckle and retains them in alignment.

It will be noted that the knife housing 76 and the stop member 86 are built with elongated bolt apertures and are adjustable to cut and form buckles of various sizes. It will also be noted that the mounting may be actuated by a foot power or a hand power press or be motor driven.

In general the buckle frame is formed from a rigid or semi-rigid rod which is ornamentally covered by a strip of fabric having both side edges thereof either sewed together or joined together by heat and pressure.

In bending the covered rod, the covering material is formed to provide a rib, the rib being located within the confines of the buckle and is continuous and in one plane.

It is further to be noted that the shape of the buckle may be other than rectangular and that in all cases, the device cuts and forms the buckle, etc., in one operation.

It is also to be noted that in the embodiment shown the free end of the forming die 48' is bent inwardly to bring its roller in alignment with the roller on the forming die 48.

In accordance with the patent statutes I have described and illustrated the preferred embodiment of my invention, but it will be understood that various changes and modifications can be made therein without departing from the spirit of the invention as defined by the appended claims.

I claim:

1. In a press having a bed and a plunger rod, a mounting for buckle forming dies for buckles made of a cut length of covered wire, comprising a carrier plate secured to said bed by brackets and extending in upright position in front of said press, said carrier plate having an elongated upright slot centrally thereof, two elongated forming dies positioned in equally spaced apart relation from the center of said slot and being vertically slidably mounted on said plate, a T-bar secured to said plunger rod and carrying an upright bar in alignment with said slot, said upright bar having a laterally extending member passing through said slot and carrying a horizontally positioned supporting bar for said vertically mounted forming dies, said forming dies respectively carrying two rollers in juxtaposed relation, a rectangular mandrel fixed to the front face of said carrier plate, said rollers being positioned to engage said wire and form downwardly bent sides and prevent rebending of said bent sides, two further forming dies pivotally mounted on said carrier plate below said mandrel and being spring urged away from said mandrel, said vertical forming dies having bevelled lower ends contacting said further dies when lowered and causing movement of said further dies against the lower ends of said bent wires into buckle forming closing relation and with said wire end portions in contact with the lower face of said mandrel, a stripper having two arms and being slidably mounted rearward

of said carrier plate, said stripper being spring-urged rearward of said mounting, said carrier plate having two openings at the vertical sides of said mandrel and through which said stripper arms are movable forwardly to eject said completed buckle, means for moving said stripper forwardly to eject said buckle, and a collector member secured to the central portion of said mandrel and shaped to direct said buckle rearwardly to a container positioned rearward of the front face of said mounting.

2. In a press having a bed and a plunger rod, a mounting for buckle forming dies for buckles made of a cut length of covered wire, comprising a carrier plate secured to said bed by brackets and extending in upright position in front of said press, said carrier plate having an elongated upright slot centrally thereof, two elongated forming dies positioned in equally spaced apart relation from the center of said slot and being vertically slidably mounted on said plate, a T-bar secured to said plunger rod and carrying an upright bar in alignment with said slot, said upright bar having a laterally extending member passing through said slot and carrying a horizontally positioned supporting bar for said vertically mounted forming dies, said forming dies respectively carrying two rollers in juxtaposed relation, a rectangular mandrel fixed to the front face of said carrier plate, two further forming dies pivotally mounted on said carrier plate below said mandrel and being spring urged away from said mandrel, said vertical forming dies having bevelled lower ends contacting the ends of said wire and forming downwardly bent sides, said rollers being positioned to engage said bent wire and prevent rebending of said bent sides, said bevelled sides contacting said further dies when lowered and causing movement of said further dies against the lower ends of said bent wires into buckle forming closing relation and with said wire end portions in contact with the lower face of said mandrel, a stripper having two arms and being slidably mounted rearward of said carrier plate, said stripper being spring-urged rearward of said mounting, said carrier plate having two openings at the vertical sides of said mandrel and through which said stripper arms are movable forwardly to eject said completed buckle, means for moving said stripper forwardly to eject said buckle, and a collector member secured to the central portion of said mandrel and shaped to direct said buckle rearwardly to a container positioned rearward of the front face of said mounting.

3. In a press having a bed and a plunger rod, a mounting for buckle forming dies for buckles made of a cut length of covered wire, comprising a carrier plate secured to said bed by brackets and extending in upright position in front of said press, said carrier plate having an elongated upright slot centrally thereof, two elongated forming dies positioned in equally spaced apart relation from the center of said slot and being vertically slidably mounted on said plate, a T-bar secured to said plunger rod and carrying an upright bar in alignment with said slot, said upright bar having a laterally extending member passing through said slot and carrying a horizontally positioned supporting bar for said vertically mounted forming dies, said forming dies respectively carrying two rollers in juxtaposed relation, a rectangular mandrel fixed to the front face of said carrier plate, two further forming

dies pivotally mounted on said carrier plate below said mandrel and being spring urged away from said mandrel, said vertical forming dies having bevelled sides contacting the ends of said wire and forming downwardly bent sides, said rollers being positioned to engage said bent sides and prevent rebending of said bent sides, said bevelled sides contacting rollers positioned at the upper ends of said further dies when lowered and causing movement of said further dies against the lower ends of said bent wires and inbending said bent ends into buckle forming relation and with said wire end portions in contact with the lower face of said mandrel, a stripper having two arms and being slidably mounted rearward of said carrier plate, said stripper being spring-urged in a direction rearward of said mounting, said carrier plate having two openings at the vertical sides of said mandrel and through which said stripper arms are movable forwardly to eject said completed buckle, means for moving said stripper forwardly to eject said buckle, and a collector member secured to the central portion of said mandrel and shaped to direct said buckle rearwardly to a container positioned rearward of the front face of said mounting.

4. In a mounting for buckle forming dies for buckles made of a cut length of wire, comprising a carrier plate having an elongated slot centrally thereof, two elongated forming dies positioned in equally spaced apart relation from the center of said slot and being vertically slidably mounted on said plate, an upright bar mounted in alignment with said slot, said upright bar having a laterally extending member passing through said slot and carrying a horizontally positioned supporting bar for said vertically mounted forming dies, said forming dies respectively carrying two rollers in juxtaposed relation, a rectangular mandrel fixed to the front face of said carrier plate, two further forming dies pivotally mounted on said carrier plate below said mandrel and being spring-urged away from said mandrel, said vertical forming dies having bevelled sides contacting the ends of said wire and forming downwardly bent sides, said rollers being positioned to engage said bent sides and prevent rebending of said bent sides, said bevelled sides being in contacting relation with rollers positioned at the upper ends of said further dies when lowered, and causing movement of said further dies against the lower ends of said bent wires and inbending said bent wire ends into buckle forming relation and with said wire end portions in contact with the lower face of said mandrel, a stripper having two arms and being slidably mounted rearward of said carrier plate, said stripper being spring-urged in a direction rearward of said mounting, said carrier plate having two openings at the vertical sides of said mandrel and through which said stripper arms are movable forwardly to eject said completed buckle, means for moving said stripper forwardly to eject said buckle, and a collector member secured to the central portion of said mandrel and shaped to direct said buckle rearwardly to a container positioned rearward of the front face of said mounting.

5. The invention as defined in claim 4, wherein means is provided for automatically forming cut to length sections of the supply wire for each downward stroke of the vertically movable forming dies.
